UNITED STATES PATENT OFFICE

GEORGE A. SHOEMAKER, OF CHICAGO, ILLINOIS, ASSIGNOR TO BAKER-VAWTER COMPANY, OF PORTLAND, MAINE, A CORPORATION.

BINDER-LOCK.

No. 892,014.

Specification of Letters Patent.

Patented June 30, 1908.

Application filed December 21, 1903. Serial No. 186,049.

To all whom it may concern:

Be it known that I, GEORGE A. SHOEMAKER, a citizen of the United States, residing at Chicago, in the State of Illinois, have invented a new and useful Improvement in Binder-Locks, of which the following is a full and accurate description, reference being had to the accompanying drawings.

My invention relates especially to that class of binders, in which economy of construction is desired, and resides in the peculiar mechanism herein described, by which simplicity, strength and economy of manufacture is secured.

In the drawings, Figure 1 represents in perspective a binder fitted with my lock. Fig. 2 is an enlarged view of a vertical section taken through the line 2--2 of Fig. 1. Fig. 3 is a horizontal sectional view taken 20 through the line 3--3 of Fig. 1. Fig. 4 is a detail drawing of the several parts of my locking mechanism.

More particularly A and A' represent the binding bars of my binder.

B, B, represent the binding posts of my binder, which preferably consist of telescoping sections secured respectively to the bars A and A', but may be constructed of any desirable form or style or number. I prefer to 30 construct them as follows: Projecting from the bar A is a stud b. In opposition thereto, and having telescopic relation therewith, a tube b' projects from the bar A' and is fitted at its inner or free end with an inwardly 35 turned rim or shoulder b''. Fitted in the upper or free end of the stud b is a screw b³ the head of which is larger in diameter than the stud b, and is designed to engage with the rim or shoulder b'' as the sections b and b' are 40 drawn apart, thereby operating as a stop to prevent the separation of the sections b and b'.

C, C, represent the locking posts of my binder. They are identical in construction 45 and may be one or more as desired. The construction of the said locking post C is as follows:—Two tubes c and c' are attached respectively to the binding bars A and A', and have telescoping engagement, the tube 50 c' being the smaller. The inner or free end of the tube c' is slotted c² c² for the purposes hereinafter named. Lying within the tube c' and projecting from either end thereof is a shaft c³. The upper end of said shaft c³ or 55 the end nearest the binding bar A' projects

through a suitable aperture in the said bar A' and beyond the outer face of the said binding bar A'. This upper end of the said shaft is threaded c⁴ as shown in detail in Fig. 4. The lower end of the said shaft c³ is 60 fitted with a head c⁵, which is formed by a gradual enlargement of the said shaft c³ at its inner or lower end, until the shaft becomes in diameter equal in size to the diameter of the outer face of the tube c². Projecting from the face of the shaft c³ near its lower end, are one or more lugs c⁶ c⁶, which 65 engage with the said slots c². Fitted upon the upper or threaded end c⁴ of the said shaft c³ is a thumb nut c⁷, which is larger in diameter than the aperture in the said binding bar A', through which the shaft c³ projects, and said thumb nut c⁷ rests upon the outer 70 face of the said binding bar A', in operation. To prevent the thumb nut c⁷ from being removed from the end of the shaft c³ in operation, I countersink in its upper face the small screw c⁸, which I screw into the end of the shaft c³. The head of this screw c⁸ is of such 75 size as to prevent the thumb nut c⁷ from being turned free from the end c⁴ of the shaft c³.

In operation the tubes c and c' in telescopic engagement, the thumb nut being released or turned toward the outer end of the 80 shaft c³, the head c⁵ of the shaft lies outside of the tube c' and in contact with its slotted or inner end, and within the larger tube c. The thumb nut c⁷ is then turned from the end c⁴ of the shaft, the lugs c⁶ c⁶ engaged with the 85 slots c² c², preventing the shaft c³ from revolving, and the said thumb nut being shoudered upon the outer face of the binding bar A' the shaft c³ is drawn upwards through the 90 tube c'. This action draws the head c⁵ within the tube c'. The said head c⁵ being at its outer end larger than the bore of the said tube, the action of drawing the head within the tube expands the adjacent or lower end 95 of the tube c'. This expansion is made possible by the slotting c² c² of the said tube c'. The expanded end of the said tube c' thereupon impinges the inner face of the tube c, and the locking is effected by the frictional contact of the two tubes.

The operation of releasing the lock is the reverse of the one just described. The release of the shaft c³ by turning the thumb screw c⁸ toward the end c⁴ of the shaft, allows the head c⁵ to be forced out of the lower end 100 105 110

of the tube c' by the tension of the slotted end of the tube c' .

While I have described a particular construction embodying my invention, I would not be confined in the matter of detail to the same; but would claim the right to vary or modify the construction in any manner permissible within the spirit of my invention. Covers may be employed if desired.

10. What I claim is—

1. In a binder, the combination with binding bars, and binding posts, of a locking post, comprising two telescoping tube sections attached respectively to said binding bars, the smaller of which sections is fitted at its inner or telescoping end with slots, a shaft extending through said smaller tube, its lower end being enlarged to a diameter larger than that of the bore of said smaller section, extending beyond and adjacent to the said slotted end of said smaller section, lugs extending from the face of said shaft
- 15
- 20

and engaging said slots, the upper end of said shaft being threaded and projecting from said smaller tube, and through a suitable aperture beyond the outer face of the adjacent said binding bar, and a thumb nut larger in diameter than said aperture, engaging said threaded end of the said shaft, substantially as described, and for the purposes herein set forth.

2. A loose leaf binder comprising in combination with covers, a tube fastened to the inside face of one cover, a tube open at both ends and fastened to the other cover and telescoping with the first tube and having a split end, means for expanding the end to clamp the outer tube, and means closing the outer mouth of the inner tube and arranged to operate said expanding means.

GEORGE A. SHOEMAKER.
